Primary Examiner — Barbara Fox*Assistant Examiner* — Michael L Lemmons(74) Attorney, Agent, or Firm — HSML P.C.(57) CLAIM

The ornamental design for a kitchen knife as shown and described.

DESCRIPTION

FIG. 1 is a perspective view of a kitchen knife showing my new design;

FIG. 2 is a front elevation view thereof;

FIG. 3 is a rear elevation view thereof;

FIG. 4 is a top view thereof;

FIG. 5 is a bottom view thereof;

FIG. 6 is a left side view thereof;

FIG. 7 is a right side view thereof;

FIG. 8 is a view of the detail 8-8 in FIG. 2; and,

FIG. 9 is an enlarged sectional view along line 9-9 in FIG. 8.

The broken lines are disclaimed and form no part of the claimed design. The surface shading lines depict the character or contour of the surfaces represented and are not themselves part of the claimed design.

1 Claim, 4 Drawing Sheets(56)
